[57] CLAIM

The ornamental design for a desk pen set base, as shown and described.

DESCRIPTION

FIG. 1 is a perspective view of a desk pen set base showing my new design;

FIG. 2 is a top plan view thereof;

FIG. 3 is a front elevational view thereof;

FIG. 4 is a rear elevational view thereof; and
FIG. 5 is a cross-sectional view taken on line 5—5 of
FIG. 3.

The bottom of the base is plain and unornamented except for the cylindrical support members.

Fig. 1.Fig. 2.Fig. 3. → 5Fig. 4. → 5Fig. 5.
